No. 667,329.

Patented Feb. 5, 1901.

W. W. MARSH & C. H. HACKETT.
CENTRIFUGAL LIQUID SEPARATOR.

(No Model.)

Fig. 1.

UNITED STATES PATENT OFFICE.

WILBUR W. MARSH AND CHARLES H. HACKETT, OF WATERLOO, IOWA.

CENTRIFUGAL LIQUID-SEPARATOR.

SPECIFICATION forming part of Letters Patent No. 667,329, dated February 5, 1901.

Application filed October 5, 1900. Serial No. 32,090. (No model.)

To all whom it may concern:

Be it known that we, WILBUR W. MARSH and CHARLES H. HACKETT, citizens of the United States of America, and residents of Waterloo, Black Hawk county, Iowa, have invented certain new and useful Improvements in Centrifugal Liquid-Separators, of which the following is a specification.

Our invention relates to that class of separators in which liquids whose constituents are of different specific gravities are separated by centrifugal force, and has for one of its objects the provision of segmental conical plates movably attached to an interior liner, so arranged within the separator as to deflect the heavier particles from the lighter and separate them respectively for distribution into their proper receptacles.

Other objects of our invention are to render the cleaning of the separator easier by making the segments of the plates movable and to render the liner more readily introduced into or removed from the cylinder by the compact arrangement of its plates when they are compressed upon each other and against the liner.

These objects we accomplish in the manner and by the means hereinafter more fully described in detail and particularly pointed out in the claims, reference being had to the accompanying drawings, in which like numbers indicate like parts throughout the several views.

Figure 1 is a side elevation of a separator in section, showing our segmental conical plates pivotally mounted on the liner therein. Fig. 2 is a top plan view of the segmental conical plates as seen from a position indicated by the line x x in Fig. 1, and Fig. 3 is a detail showing the segmental plates placed in different positions for the purpose of cleaning them.

Our invention is intended particularly as an improvement on the Patent No. 640,130, issued December 26, 1899, to Charles H. Hackett and Christian E. Dailey, of Waterloo, Iowa, and the construction of the separator-bowl is the same as shown therein. Our improvement, however, is capable of being adapted to conform to the interior construction of other forms of separator-bowls.

The liner consists of the uprights 1, at-

tached at the top to the ring 3 and at the bottom to the ring 4.

The plates 2 and 2' are constructed in the form of segments of the surface of a truncated cone of sufficient width that they may overlap each other when in a state of rest and are curved into such a shape that when thrown out horizontally as an effect of centrifugal force their vertical edges will nearly coincide and the middle part of their outer edges touch the inner periphery of the cylinder 7, in which they are contained. The curve of the outer edges of each plate is so formed that only the middle portion thereof can come into contact with the inner periphery of the cylinder, those parts of the edge nearest the outer corners of the plate being cut away sufficiently to leave a space between them and the inner wall of the cylinder 7 when in revolution. This is shown in Fig. 2 by the dotted lines, the outer dotted line indicating the position of the inner periphery of the cylinder and the inner dotted lines the positions of the plates when pressed against the cylinder. The plates are hinged at the middle portion of their lower edges by means of hinges 9, pivoted to the outer edges of the ribs 1 in such a manner that each series of segmental plates is above the series of plates below, like surfaces of inverted truncated cones, at any distance apart which may be considered desirable. It is to be understood that any number of segmental plates or series of plates may be used and that they may be pivoted to the uprights of the liner by any other suitable or equivalent form of hinge or pivot. The drawings represent the segmental plates as compressed against the liner in the position which they are placed when they are introduced into the cylinder and indicate the ease with which they may be placed within or removed therefrom. The dotted lines represent the manner in which the plates spread to fill the space in the cylinder to its inner periphery when the apparatus is rapidly revolved.

The centrifugal force which spreads the plates into the position shown causes the heavier particles of the milk which has been introduced into the cylinder 7 at the opening 8 to separate from the lighter and to seek its inner wall. As the particles of the skim-

milk on account of their greater weight find their way to the inner wall of the cylinder, the lighter particles of cream tend to find their way to the center. The skim-milk 5 coming in contact with the upper surfaces of the upper series of segmental plates finds its way down the inner wall of the cylinder through the spaces left between the cylinder and the cut-down outer edges of the plates. 10 The retarding of the descent of the milk by means of the interposing plates allows the minuter particles of the cream not heretofore separated therefrom to become separated and flow toward the center of the liner 15 along the under surfaces of the plates. This process by retarding the movement of the milk toward the bottom of the cylinder allows it to become completely exhausted of the minuter particles of cream commonly 20 wasted in the ordinary type of separator. The skim-milk is then discharged through the pipe 6, which opens into the separator near its inner wall, while the cream is discharged in the usual manner through the conduit at the center of the bottom of the separator at 5.

Instead of the separator 7 any other similar receptacle may be used wherein our series of improved segmental plates can be 30 closed arranged to spread to meet the inner periphery of the bowl. This manner of construction, embodying the pivotal attachment of curved plates in the form of portions of the surface of truncated cones to the inner

liner, allows the apparatus to be easily introduced into or withdrawn from the cylinder of the separator when the plates are pressed up into close contact with the liner. The pivotal attachment of the segmental plates permits them to be easily moved up or down 35 and cleaned, as is shown in Fig. 3.

Having thus described our invention, what we claim as new, and desire to secure by Letters Patent, is—

1. In a centrifugal liquid-separator, a liner 45 provided with series of separated plates in the form of segments of an inverted truncated cone pivotally mounted thereon, substantially as shown and described.

2. In a centrifugal liquid-separator, a liner 50 composed of the uprights 1 attached to the rings 3 and 4, in combination with the segmental plates 2 and 2', pivotally attached thereto by the hinges 9, substantially as shown and described.

3. In a centrifugal liquid-separator, in combination, the cylinder 7, the liner composed of the uprights 1 and rings 3 and 4, the segmental plates 2 and 2' pivotally connected to the uprights 1 by hinges 9, all substantially 55 as shown and described.

Signed at Waterloo, Iowa, this 2d day of October, 1900.

WILBUR W. MARSH.
CHARLES H. HACKETT.
